UNITED STATES PATENT OFFICE.

JERRY JIROUSEK AND EDWARD HOLAN, OF VERDIGRE, NEBRASKA.

DESIGN FOR A PINCUSHION.

45,009.

Specification for Design.

Patented Dec. 9, 1913.

Application filed May 19, 1913. Serial No. 768,675. Term of patent 7 years.

To all whom it may concern:

Be it known that we, JERRY JIROUSEK and EDWARD HOLAN, citizens of the United States, residing at Verdigre, in the county of Knox and State of Nebraska, have invented a new, original, and ornamental Design for Pincushions, of which the following is a specification, reference being had to the accompanying drawing, forming part thereof.

Figures 1 and 2 are side elevations of a

pin cushion according to our invention. Fig. 3 is a top plan view of Fig. 1.

We claim:

The ornamental design for a pin cushion as shown.

JERRY JIROUSEK.
EDWARD HOLAN.

Witnesses:

JOHN BLEZEK,
JOHN BERAN.
